CLAIM

The ornamental design for a handle for ratchet assembly, as shown and described.

DESCRIPTION

FIG. 1 is a front, top, and side perspective view of a handle for ratchet assembly, in accordance with our new design; FIG. 2 is a top plan view of the handle for ratchet assembly shown in FIG. 1;

FIG. 3 is a side elevation view of the handle for ratchet assembly shown in FIG. 1, taken from the right side of FIG. 1;

FIG. 4 is a side elevation view of the handle for ratchet assembly shown in FIG. 1, taken from the left side of FIG. 1;

FIG. 5 is a bottom plan view of the handle for ratchet assembly shown in FIG. 1;

FIG. 6 is a front elevation view of the handle for ratchet assembly shown in FIG. 1; and,

FIG. 7 is a rear elevation view of the handle for ratchet assembly shown in FIG. 1.

The broken lines illustrate environmental structure which forms no part of the claimed design.
